UNITED STATES PATENT OFFICE.

HENRY A. TOBEY, OF LIMA, OHIO.

WATER-HEATER.

SPECIFICATION forming part of Letters Patent No. 353,097, dated November 23, 1886.

Application filed June 17, 1885. Serial No. 168,980. (No model.)

To all whom it may concern:

Be it known that I, HENRY A. TOBEY, a citizen of the United States, residing at Lima, in the county of Allen and State of Ohio, have 5 invented certain new and useful Improvements in Water-Heaters; and I do hereby declare the following to be a full, clear, and exact description of the invention, such as will enable others skilled in the art to which it appertains to make 10 and use the same.

The common forms of water-heaters in general use consist of a shell or receiver in which there is a coil or series of pipes, which pipes are connected at one end with the steam-supply pipe and at the other end with a steam-trap. 15 Cold water is admitted at the bottom of the shell and hot water is discharged from the top. The valve in the steam-supply pipe is opened as much as may be required and a constant 20 current of steam admitted to the steam-coil.

The objections to such a heater are that at times when little or no hot water is being used—at night, for example—the water in the heater becomes so hot that a portion of it is converted 25 into steam, which rises to the top of the heater, displaces the water and forces it back into the cold-water tank. Thus, as often occurs, all the water in the cold-water tank may become heated and accidents happen by 30 scalding, hot water being discharged from a supposed cold-water faucet. When a hot-water faucet is opened, if there is steam in the heater, it must all be allowed to escape before 35 water can be obtained. Besides the inconvenience and danger, there is a great waste of heat and consequent unnecessary expenditure of fuel.

The receiver for the shell of an ordinary heater must be large, so as to contain a reservoir 40 of hot water to meet a large demand or draft from the heater, which becomes cooler as it is drawn off, and consequently such heaters are bulky and expensive, and having so much surface they waste a great deal of heat by radiation.

The object of my invention is to overcome 45 these objections; and to this end it consists of mechanisms hereinafter described, and particularly claimed.

50 My invention is illustrated in the accompanying drawings, in which Figure 1 is a central

longitudinal section showing the different parts of the device; Fig. 2, a view showing a modification in the form of the shell or body that may be used instead of that shown in Fig. 55 1; and Fig. 3 is a perspective view of a segment of the heater, showing the lever and valve connections, with the body of the heater broken away to show the arrangement of the steam or heating-pipes and the expansive or 60 discharge-water-pipe.

In the drawings, A is the receiver or body of the heater, which is composed of a shell, C, secured to ends B and B'; or which may be composed of two separate iron pipes put together by suitable connections, as shown in Fig. 2.

D is a hollow casting, into which are fastened at one end the pipes E, they freely communicating with its interior. A tubular projection, d, of said casting passes out of receiver A through an opening in flexible plate o, and has screwed onto it valve F, flexible plate o being held between their annular surfaces. The opposite ends of pipes E are secured 70 in suitable perforations or holes in plate G. Cap H is of the same diameter as plate G, and is made bulging, which forms a space between it and plate G, to admit of a free circulation 75 of steam between it and the ends of pipes E. Cap H rests against plate G, and plate G against end B', and they are both held securely in place by bolts passing through them into rim e', around opening e in end casting B'. Tubular projection a forms a connection for a steam 80 trap or pipe for discharging the water of condensation from pipes E.

J is a tube of some metal that has a large ratio of expansion by heat—for instance, brass—which is located in the upper part of 85 chamber A. One end of tube J extends through and is rigidly fastened to end casting, B', at g, and connects with the hot-water - discharge pipe R. The other end is plugged or shut and rests against flexible plate o', and has screwed 90 into it, through an opening in diaphragm or flexible plate o', extension shaft or arm m, said flexible plate being pressed between annular surfaces on said pipe and arm.

ii are perforations in pipe J, to admit water 95 from chamber A to said pipe. They are located near the end of the pipe that rests against

flexible plate σ' . Flexible plate σ closes opening n in end casting B , and is held in place by flat ring or circular casting P pressing its margin or edge between it, and a rim around opening n , said ring being firmly bolted to said rim. Flexible plate σ' is secured in position in the same manner by ring P' . Ring P' has brackets or projections $q q$, Fig. 3, which support the fulerums of lever L .

10 L is a lever of suitable strength, which has its fulerum at r by a suitable connection with brackets $q q$. The short arm of said lever is acted upon by extension-arm m , with which it has a suitable connection at t , Fig. 1, and the 15 long arm acts upon valve-stem w , with which it is connected, in a manner hereinafter described.

10 Valve F may be a valve of any kind, so that movement of the valve-stem outward or to 20 the left, as shown in the drawings, opens the valve, and a reverse movement closes it. A balanced or easily-operated valve, however, is preferable. $u u$, Fig. 3, are arms made fast to the shell of valve F , to the outer or free 25 ends of which cross-bar v is secured, which acts as a guide for and supports the outer end of valve stem w .

30 $x x'$ are rings or nuts connected to valve-stem w , which is screw-threaded to receive them. They may be thus turned and secured at any suitable point on the valve-stem.

35 y is a spiral spring, of suitable strength, encircling valve-stem w , the fixed end of which presses against cross-bar v , and the other or movable end against lock-nuts $x x$. The opposite sides of nuts $x x$ press against suitable bearings made on the fork at the end of the long arm of lever L .

40 Q is the inlet or water-supply pipe to the heater, and R is the discharge-pipe.

45 S is the inlet or supply steam pipe to water-valve F , and T is the discharge-pipe for water of condensation from pipes E .

The operation of the device is as follows: 50 Steam is admitted by valve F through hollow casting D to pipes E , and gives off its heat to the water surrounding said pipes, and the water of condensation is discharged through pipe T , to which a suitable steam-trap should be attached. Water admitted to heater at Q must pass lengthwise with pipes E and rise between them to get to openings $i i$ in pipe J to be discharged, and will thus rapidly become heated by contact with said pipes. Besides 55 the current or movement given the water by its passage from inlet to outlet, the hottest portion of the water would naturally rise to the top of the heater. Water before being discharged enters pipe J at openings $i i$, and

60 passes through said pipe its entire length. Thus its internal and external surfaces coming in contact with the water being discharged and that at the top of the heater, its temperature must be the same as that of the water, 65 and any changes in the temperature of the water instantly changes the temperature of the pipe. Pipe J , as before stated, is a tube

of some suitable metal having a higher ratio of expansion by heat than iron, of which the shell of the heater is made, and therefore as the temperature of the water rises the difference in the relative lengths of pipe J and the shell of the heater increases. As pipe J is made rigidly fast to end casting B' , 70

75 there can be no motion in that direction; consequently the motion obtained by the increased length of said pipe must operate in the opposite direction, which is provided for by flexible plate or diaphragm σ' , which readily springs outward and inward as said pipe expands and contracts. As expansion occurs in pipe J extension-arm m is pushed outward and traction on short arm of lever L is relieved, which action diminishes the resistance of long arm of

80 said lever to the action of spring y , allowing it to push the stem of valve F inward, thus closing the valve and shutting off steam from 85 heating-pipes E . It will be seen that if pipes E are of the same metal as pipe J this expansion will facilitate the closing of valve F , 90

95 they being held stationary by plate G , which is bolted to end casting B' , their motion is imparted to the body of valve F , pushing outward, or in an opposite direction to the movement of the valve-stem. Flexible plate σ is to allow for this motion. When hot water is 100 drawn from the heater, cold water is admitted to replace it, which lowers the temperature of the pipes, causing them to contract or shorten, and reverses the operation just described.

105 Valve F therefore is opened and shut automatically by the expansion and contraction principally of pipe J ; or, in other words, the temperature of the water in the heater controls and regulates the supply of steam to the 110

115 heater. Slight motion of short arm of lever L is many times multiplied by long arm of said lever at its connection with valve stem w . Therefore only a few degrees variation of temperature in pipe J is required to open and close valve F .

120 Water drawn from the heater will therefore always be of nearly the same temperature, whether much or little be taken. If draft be made on the heater to its entire capacity, valve F will be opened wide and 125 pipes E filled with steam at boiler-pressure, while, on the contrary, if but little water be taken, said valve will be but slightly opened.

130 Any temperature that may be desired may be given the water by lock-nuts $x x$. For example, if they be moved outward on valve-stem, a greater contraction of pipe J is required to open valve F , and less expansion to close said valve; consequently the steam would be shut off by a lower temperature of 135 the water.

140 As the water is heated as rapidly as drawn, no reservoir or storage of hot water to meet a large demand is required; consequently the receiver need be only of sufficient capacity to 150 contain pipes E and J in their proper relations and admit of a free circulation of water.

155 The shell or body of a heater, therefore, that will supply a large quantity of hot water may

be comparatively small, requiring but little space and offering but little surface for heat to radiate from.

The diameter of opening *e* in end casting *B*' is 5 greater than that of casting *D*, therefore when it is desirable to remove pipes *E* for the purpose of cleaning lime or sediment from them, it can readily be accomplished by detaching valve *F* from its connection with casting *D* and 10 removing cap *H*, when pipes *E*, with casting *D* and plate *G*, are free to be drawn out and be removed.

My improved heater has the least possible amount of surface from which heat can radiate, and may be made to discharge either warm 15 or hot water always at uniform temperature, and when the valve is properly set by lock-nuts the receiver can never fill with steam.

Having thus described my invention, what 20 I claim is—

1. In combination with a water-heater, a source of heat in connection therewith, a valve controlling such source of heat, an expansible body attached at one end to the interior of the 25 water-heater and extending outside of the same, and a lever connecting the expansible body and the valve, substantially as set forth.

2. The combination, with a water-heater, of a source of heat in connection therewith, a 30 valve controlling such source of heat, having a stem provided with a spring and locking mechanism, the expansible pipe attached at one end to the interior of the water-heater and extending outside of the same, and a lever 35 connecting said valve-stem and expansible pipe, whereby by the greater or less expansion of the pipe the valve is operated to regulate the admission of the heat and thus control the 40 temperature of the water, substantially as described.

3. In combination with a water-heater, a valve controlling the source of heat, an expansible tube within the water-heater and made fast at one end thereto, and a flexible diaphragm connected with said valve, and against 45 which diaphragm the opposite end of the said tube rests and exerts pressure upon as it expands, substantially as described.

4. The combination, with a water-heater in 50 connection with a source of heat and a valve controlling such source of heat, of the expansible pipe within the heater provided with apertures for the admission therein of the water to be discharged, with one end of the 55 pipe rigidly secured to the casing, and a flexible diaphragm in the casing against which the opposite end of the expansible pipe rests, the lever connected to said valve, and an extension-arm connecting said lever to the said dia- 60 phragm and pipe, whereby the expansion and contraction of said pipe serve to move said diaphragm and lever, substantially as and for the purpose set forth.

5. The shell or body of the heater provided with heating-pipes, in combination with a 65 flexible diaphragm in one end of the heater, a valve controlling the source of heat, a hollow casting in the heater supporting the said pipes at the same end, and provided with a neck extending through said diaphragm and connected with and supporting the valve, a ring 70 to hold the diaphragm between the valve and the said neck, and a rigid plate at the opposite end of the heater, to which the said pipes at that end are secured, whereby the series of 75 heating-pipes are supported within the body of the heater, and a lateral expansion of the pipes in one direction permitted, substantially as and for the purpose described.

6. In a water-heater provided with a valve 80 mechanism controlling the source of heat, in combination with a water-inlet located near one end of the heater, the expansion-pipe connected to said valve mechanism and extending to and provided with openings near the 85 other end of the heater, and heating-pipes placed within the heater and arranged, as shown, above said inlet, whereby water admitted to the heater is compelled to pass lengthwise with said heating-pipes, rise be- 90 tween them, and become heated before reaching the expansion-pipe, and the said pipe is kept constantly at the same temperature of the surrounding water, substantially as described.

7. The water-heater casing, in combination 95 with the valve-casing, valve mechanism consisting of the valve, valve-stem, valve-arms, cross-arm, the coiled spring on valve-stem, and the locking-nuts, the steam-pipe fixed at one end to the valve-casing, the flexible dia- 100 phragm, and the expansion device within the casing connected to the valve, substantially as and for the purpose described.

8. In combination with the casing and expansible tube within the casing, the lever, a 105 steam inlet pipe, a valve fixed to said pipe, and the screw-threaded valve-stem, the latter provided with a coiled spring and locking nuts or rings *x* *x'*, substantially as and for the purpose described.

9. The lever mechanism consisting of the long arm forked at its lower end and the extension-piece *m*, to which the short arm of the lever is connected, and the brackets *q*, to which the lever-arm is pivoted, in combination with 115 the heater-casing, the expansible tube within the casing, the valve, and the steam-inlet pipe, substantially as described.

In testimony whereof I affix my signature in presence of two witnesses.

HENRY A. TOBEY.
